US00D936746S

(12) **United States Design Patent** (10) Patent No.: **US D936,746 S**
Peeters et al. (45) Date of Patent: **** Nov. 23, 2021**

(54) **GAME BOARD AND GAME PIECES**

(71) Applicant: **SMART N.V.**, Kontich (BE)

(72) Inventors: **Raf Peeters**, Lier (BE); **Leighton Meredith Rees**, Cirencester (GB)

(73) Assignee: **SMART N.V.**, Kontich (BE)

(**) Term: **15 Years**

(21) Appl. No.: **29/688,295**

(22) Filed: **Apr. 19, 2019**

(30) **Foreign Application Priority Data**

Oct. 30, 2018 (EM) 005813094

(51) LOC (13) Cl. **21-01**

(52) U.S. Cl.

USPC **D21/360**; D21/350; D21/334

(58) **Field of Classification Search**

USPC ..... D21/334, 335–342, 355–359, 365, 318, D21/397, 351, 385, 386, 389, 404, 478, D21/479, 483–486, 489–491, 493, 494, D21/497, 499, 507, 510, 511, 561; 273/241, 242, 244–247, 259, 271–281, 273/282.1–282.3, 284, 287, 317.3, 108.1, 273/108.5, 118 D, 236–240, 283, 309, 273/441, 461, 288–290, 153 R, 156, 273/153 S; D6/406.1, 406.3, 406.4, D6/406.6; D19/86, 92, 95, 87, 113, 75, D19/77, 78, 80, 60, 59, 64, 63; 108/14, 108/62, 43, 67; 434/81, 82, 96, 128, 365, 434/393, 403, 428, 429, 433, 416, 247, 434/248, 251, 408, 413, 145, 430; 446/82–84, 85, 97, 99, 101, 102, 118, 446/124, 268, 330, 476, 491, 901

CLAIM

The ornamental design for a game board and game pieces, as shown and described.

DESCRIPTION

FIG. 1 is a top perspective view of the game board component shown separately for clarity of illustration; FIG. 2 is a front elevational view of the game board of FIG. 1; FIG. 3 is a rear elevational view of the game board of FIG. 1; FIG. 4 is a right side view of the game board of FIG. 1; FIG. 5 is a left side view of the game board of FIG. 1; FIG. 6 is a top view of the game board of FIG. 1; FIG. 7 is a bottom view of the game board of FIG. 1; FIG. 8 is a top perspective view of a game piece, shown separately for clarity of illustration; FIG. 9 is a front elevational view of the game piece of FIG. 8; FIG. 10 is a rear elevational view of the game piece of FIG. 8; FIG. 11 is a left side view of the game piece of FIG. 8; FIG. 12 is a right side view of the game piece of FIG. 8; FIG. 13 is a top view of the game piece of FIG. 8; FIG. 14 is a bottom view of the game piece of FIG. 8; FIG. 15 is a top perspective view of a game piece, shown separately for clarity of illustration;

FIG. 16 is a front elevational view of the game piece of FIG. 15; FIG. 17 is a rear elevational view of the game piece of FIG. 15; FIG. 18 is a left side view of the game piece of FIG. 15; FIG. 19 is a right side view of the game piece of FIG. 15; FIG. 20 is a top view of the game piece of FIG. 15; FIG. 21 is a bottom view of the game piece of FIG. 15; FIG. 22 is a top perspective view of a game piece, shown separately for clarity of illustration; FIG. 23 is a front elevational view of the game piece of FIG. 22; FIG. 24 is a rear elevational view of the game piece of FIG. 22; FIG. 25 is a left side view of the game piece of FIG. 22; FIG. 26 is a right side view of the game piece of FIG. 22; FIG. 27 is a top view of the game piece of FIG. 22; FIG. 28 is a bottom view of the game piece of FIG. 22; FIG. 29 is a top perspective view of a game piece, shown separately for clarity of illustration; FIG. 30 is a front elevational view of the game piece of FIG. 29; FIG. 31 is a rear elevational view of the game piece of FIG. 29; FIG. 32 is a right side view of the game piece of FIG. 29; FIG. 33 is a left side view of the game piece of FIG. 29; FIG. 34 is a top view of the game piece of FIG. 29; FIG. 35 is a bottom view of the game piece of FIG. 29; FIG. 36 is a top perspective view of a game piece, shown separately for clarity of illustration; FIG. 37 is a front elevational view of the game piece of FIG. 36; FIG. 38 is a rear elevational view of the game piece of FIG. 36; FIG. 39 is a left side view of the game piece of FIG. 36; FIG. 40 is a right side view of the game piece of FIG. 36; FIG. 41 is a top view of the game piece of FIG. 36; FIG. 42 is a bottom view of the game piece of FIG. 36; and, FIG. 43 is a top perspective view of the game board and game pieces in accordance with our new design.

The evenly-dashed broken lines in the drawings illustrate the portions of the game board and game pieces that form no part of the claim. The difference in cross-hatching patterns in FIGS. 1-6 is used to indicate contrasting colors.
